Fig. 3

FIGURE 1 is an end elevational view of a multiple seating unit embodying my design.

FIGURE 2 is a fragmentary front elevational view thereof.

FIGURE 3 is a front perspective view of the multiple seating unit, the center portion of the horizontal support being broken away for convenience of illustration.

The dominant features of my design reside in those portions shown in full lines on the drawing.

The rear elevation is substantially identical with the front elevation illustrated in FIG. 2.

I claim:

The ornamental design for a multiple seating unit, as shown and described.
